United States Patent Office

Des. 182,917
Patented May 27, 1958

182,917

AUTOMOBILE MAT

Emanuel Meyer, Philadelphia, Pa.

Application December 23, 1957, Serial No. 48,983

Term of patent 14 years

(Cl. D9—6)

FIG. 1

FIG. 2

FIG. 3

FIG. 4

Fig. 1 is a top plan view of an automobile mat embodying my new design.

Fig. 2 is an enlarged fragmentary sectional view taken along lines II-II of Fig. 1.

Fig. 3 is an enlarged fragmentary sectional view taken along lines III-III of Fig. 1 with a portion shown broken away in part for convenience of illustration.

Fig. 4 is an enlarged fragmentary sectional view taken along lines IV-IV of Fig. 1.

The diamonds shown in Fig. 1 are shaded to show color contrast.

I claim:

The ornamental design for an automobile mat, as shown and described.
